UNITED STATES PATENT OFFICE.

GEORGE C. BROWN, OF NEW LONDON, CONNECTICUT.

STORAGE-BOX FOR SENSITIZED PAPER.

987,952.

Specification of Letters Patent. Patented Mar. 28, 1911.

Application filed June 16, 1910. Serial No. 567,146.

To all whom it may concern:

Be it known that I, GEORGE C. BROWN, a citizen of the United States, residing at New London, in the county of New London and State of Connecticut, have invented certain new and useful Improvements in Storage-Boxes for Sensitized Paper, of which the following is a specification.

The object of this invention is to provide 10 a convenient, and reasonably cheap, form of light-tight storage receptacle for sensitized papers, such as "blue print" paper, "Van-dyke process" paper, and the like.

Briefly described, my said invention consists of a suitable housing, preferably of cylindrical form, having revolvably journaled therein a mandrel upon which a roll of sensitized paper may be mounted. The said housing is provided with a longitudinal slit 20 through which the web of paper may be withdrawn from the housing, as needed, and means is provided for measuring off so much of the said web as may be required. Provision is made for holding the said web to 25 prevent the cut end from being displaced and drawn back into the housing, and a shutter is also provided for covering the said longitudinal slit so as to exclude all light from the interior of the housing.

30 In order to explain my invention clearly I have provided the annexed drawings, in which—

Figure 1 is a front side view of a light-tight receptacle embodying my present improvements, illustrating also the manner of tearing off a section of the paper. Fig. 2 is a relatively enlarged longitudinal, central, sectional, view of the same. Figs. 3, 4 and 5 are relatively enlarged, transverse, sectional 40 views of my said device; Fig. 3 showing the shutter in its closed position and Fig. 4 showing the shutter opened to expose the longitudinal slit through which the web of paper may be drawn outward. Fig. 5 is a 45 similar view, showing the end of the paper drawn outward and in the act of being torn off.

Referring to these drawings, the numeral 10 indicates the fixed or non-rotatable housing of my device, the same being cylindrical, as here shown. Within the housing 10 is a cylindrical tube 11 one end of which is permanently closed by means of a head 12 whose inner face is provided with a central 50 projection or spur 12^a. The other end of said tube is provided with a removable cover

13 having a similar spur 14; said cover being preferably arranged to screw upon the tube 11.

The housing 10 is designed to be permanently fastened to a wall, or other fixed object, within easy reach and its front side is provided with a longitudinal slit 15, the upper edge of which serves as a straight, knife-sharp, cutting edge against which the paper 60 may be torn, as will be understood by reference to Fig. 1 of the drawings.

The inner tube 11 is adapted to be rotated a limited distance, within the fixed housing, and has longitudinal, overlapping 70 portions 11^a, forming an outlet-throat. By preference, I provide on the upper overlapping portion a shutter 11^b, of spring material, which is curved downward (as shown in Figs. 3, 4, and 5) so as to bear upon the 75 exterior surface of the inner tube in advance of the said outlet-throat; the shutter thus subserving the dual function of preventing light entering the tube 11 and a resilient means to prevent falling back into the inner 80 tube of the section of the paper protruding through the outlet-mouth or throat of said tube.

The roll of paper 16 is supported on a mandrel 17 that is mounted to revolve freely 85 on the studs 12^a and 14.

In the operation of loading my described receptacle, the cover 13 is removed and a roll of paper is slipped onto the mandrel 17, the tube 11 being removed (endwise) 90 from the housing, or not, as may be found most convenient. As the roll of paper is being slipped into the tube, the free edge of said paper is guided between the overlapping edges 11^a and is caused to project beyond the yielding shutter 11^b a distance sufficient to enable the operator to grasp it with a thumb and finger and draw the paper out to any desired length. The cover 13 is then placed upon the tube 11. Ordinarily 95 the inner tube is rotated within the fixed housing sufficiently to move the shutter 11^b and the short projecting piece of paper out of register with the slit 15 of the housing, thus protecting the said paper and the slit in the inner tube from the direct rays of light that may enter the slit 15. When it is desired to remove a section of paper from the roll 16 the inner tube is grasped by its ends and is partially rotated so as to bring the spring shutter 11^b into register with the slit 15 and, simultaneously, to cause the ex- 100 105 110

posed end of the paper to lie in said slit, as seen in Fig. 4, so that said end may be grasped. The paper is then drawn outward, through the narrow throat between the shutter 11^b and the inner wall of the tube 11, and through the slit 15 until the desired length of paper has been exposed, when the inner tube is rocked partly back to its initial position and the paper is then torn off 10 against the straight-edge formed by the upper wall of the slit 15, as seen in Figs. 1 and 5; said upper wall being suitably formed to provide a sufficient cutting edge. This leaves a short section of the paper projecting outward beyond the shutter 11^b. The tube 11 is then rocked completely back to its initial position thus moving said projecting section of paper into the darkened space between the inner tube and the housing 10, as 15 seen in Fig. 3 of the drawings. When it is again desired to obtain a piece of the paper on roll 16 the inner tube is rocked into the position seen in Fig. 4, thus causing the said projecting section of paper to be exposed 20 in slit 15 so it (the paper) may be grasped, as I have already explained.

In order that the desired length of paper may be conveniently measured, I provide on the fixed housing 10 a spring tape measure 18 which may first be drawn out to the desired length. The paper is then drawn out to correspond with the said measure and the measure is then snapped back into its case before the paper is torn off. 25

The spring shutter 11^b not only serves to 35 prevent the light from entering the tube 11 but it also serves to prevent the retraction of the cut end of the paper into the tube.

My described device may be cheaply produced; it takes up practically no more space 40 than the tin cylinders ordinarily used for storing sensitized paper, and it effectually protects the said paper from the deleterious effects of the actinic rays of light.

Having thus described my invention I 45 claim as new and desire to secure by Letters Patent:—

In a light-tight holder for sensitized paper, a stationary outer cylinder provided with a longitudinal slot, the upper wall of 50 which is formed as a sharp cutting-edge, in combination with a revoluble inner cylinder for the paper, having longitudinal overlapping portions, forming an outlet-throat, and means subserving the dual function of excluding light from said inner tube through 55 said outlet-throat and of preventing falling back into said inner tube of the section of sensitized paper protruding through said outlet-throat, comprising a shutter, of 60 spring material, carried by the upper overlapping portion and curved downward so as to bear upon the exterior surface of said inner tube in advance of said outlet-throat.

GEORGE C. BROWN.
